RAYMOND LOEWY, OF NEW YORK, N. Y., ASSIGNOR TO HUPP MOTOR CAR CORPORATION,
OF DETROIT, MICHIGAN, A CORPORATION OF VIRGINIA

DESIGN FOR A RADIATOR ORNAMENT

Application filed June 1, 1931. Serial No. 40,044. Term of patent 7 years.

To all whom it may concern:

Be it known that I, RAYMOND LOEWY, a citizen of the Republic of France, residing at New York, in the county of New York and State of New York, have invented certain new, original, and ornamental Design for Radiator Ornament, of which the following is a specification, reference being had therein to the accompanying drawings, forming a part thereof, wherein:

Figure 1 is a perspective view of my new design for radiator ornament;

Figure 2 is a side elevational view of the design shown in Figure 1; and

Figure 3 is a front elevational view of the design illustrated in Figure 1.

The dominant feature of my design consists in the wide flat base plate and the ring projecting upwardly therefrom having portions thereof extending inwardly to simulate a letter of the alphabet and to impart an ornamental appearance to the design.

I claim:

The ornamental design for a radiator ornament substantially as shown and described.

RAYMOND LOEWY.
